John D. Springer

UNITED STATES PATENT OFFICE.

EDWARD L. LIEDKE, OF SANDUSKY, OHIO.

WHIFFLETREE.

SPECIFICATION forming part of Letters Patent No. 359,873, dated March 22, 1887.

Application filed February 3, 1887. Serial No. 226,381. (No model.)

To all whom it may concern:

Be it known that I, EDWARD L. LIEDKE, of Sandusky, in the county of Erie and State of Ohio, have invented new and useful Improvements in Spring-Whiffletrees; and I do hereby declare that the following is a full, clear, and exact description thereof, reference being had to the accompanying drawings, which form a part of this specification.

10 This invention relates to certain new and useful improvements in spring-whiffletrees.

The invention consists in the peculiar construction of a jointed whiffletree, in combination with a resistance-spring, and in the peculiar construction, arrangement, and combination of the various parts, all as more fully hereinafter set forth.

Figure 1 is a top plan of my improved whiffletree. Fig. 2 is a cross-section showing construction of the hinge.

In the accompanying drawings, which form a part of this specification, A A represent two suitable members of a hinge, which are secured together by that class of hinge-joint denominated a "rule-joint," the parts being secured together by a proper bushing, B, which may be either solid or hollow, riveted on each end. Each casting A is provided on its edges with projecting lugs *a*, which serve as stops to prevent the parts moving beyond a certain point. In these castings A are fitted the whiffletree-arms C, of wood or other suitable material, and to which the draft force is applied, in the usual manner.

35 D is a semi-elliptic spring, of any desired construction, and which is banded at its longitudinal center by a band, E, said band being provided with a lug or pin, *b*, designed to engage with an elongated recess in the adjacent 40 edge of the hinge. The ends of this spring

are connected by links F to the arms C of the whiffletree, said links in their normal positions being at right angles to the longitudinal direction of the whiffletree.

The whiffletree in its normal position, under the action of the spring, is sprung back till arrested by the stops *a* upon the rear edge of the hinge. As draft force is applied the arms of the whiffletree assume the position shown in the drawings, and if the load is sufficiently heavy they are drawn forward till arrested by the front stops, *a*.

While I have described my device, broadly, as a whiffletree, it is obvious that the construction can readily be applied to either the double-tree or single-tree and still be within the spirit of my invention.

The advantages of a spring-whiffletree are so well known it is not deemed necessary to enter into a further description hereof.

What I claim as my invention is—
1. A spring-whiffletree constructed in two parts, connected together by a rule-joint provided with stops upon both edges thereof, formed by the abutting ends of the members 65 of the hinge, in combination with a spring and connecting-links, substantially as and for the purposes described.

2. A spring-whiffletree consisting of the castings A, connected together by a rule-joint provided with stops *a*, and a bushing, B, arms C, spring D, band E, links F, and pin *b*, the parts being constructed, arranged, and operating substantially in the manner and for the purposes set forth.

EDWARD L. LIEDKE.
